GRINDING MACHINE

Frank J. Horton, Hamtramck, Mich., assignor to
 Super Tool Company, Detroit, Mich., a corpora-
 tion of Michigan

Application November 9, 1940, Serial No. 364,947

1 Claim. (Cl. 51—234)

My invention relates to grinding machines, and particularly to a grinding machine and attachment in which a rotatable workpiece may be ground to cylindrical and oval form, or figures having one or any number of flat, concave, or convex sides.

The machine or attachment embodies a housing containing driving mechanism and change gear structure, all of which is mounted on a rockable bar which carries a tail stock for supporting one end of the workpiece while the other end is supported and driven by the head stock forming part of the housing and driving mechanism. Adjustable cam means regulate the degree of oscillation provided to the housing, the driving mechanism and the workpiece, toward and away from the grinding wheel. The relationship between the driving mechanism and the change gear structure controls the number of oscillations of the device and workpiece relative to a single rotation of the workpiece. When a one to one ratio obtains, a portion of the workpiece is ground over, or one side is ground concave, convex, or flat, depending upon the degree of oscillation of the workpiece. When two oscillations of the workpiece occur to a single rotation of the workpiece, two sides are ground flat, concave, or convex, the latter forming an oval shape on the workpiece. When the ratio of oscillation is three to one, a triangular form is ground on the workpiece, the sides of which may be flat, concave, or convex. Similarly, when the ratios are four to one, five to one, or any greater number, a figure having a similar number of sides is ground on the workpiece, the sides of which may be concave, convex, or flat. It will thus be seen that the device is universal in application, and when adjusted to eliminate the oscillation, a cylindrical figure may be ground on the workpiece without removing it from its supports.

Accordingly, the main objects of my invention are: to provide a machine or device for driving a workpiece in rotation and forming figures of any number of sides or shapes thereon; to provide a driving mechanism for a workpiece which oscillates the workpiece various degrees and ratios to the rotation of the workpiece for grinding various shapes thereto; to provide a pivoted bar with a housing and an adjustable tail stock and driving a workpiece mounted therebetween with mechanism within the housing which is selectively arranged to oscillate the bar and therefore the workpiece any number of times relative to a single rotation of the workpiece for ma-

ching predetermined forms thereon; to move the work support laterally across the grinding wheel as the workpiece is rotated and oscillated toward and away from the grinding wheel in a selected number of times relative to a single rotation of the workpiece to grind on a predetermined length thereof a desired form; and in general, to provide a grinding machine and attachment which is simple in construction, positive in operation, and economical of manufacture.

Other objects and features of novelty of my invention will be either specifically pointed out or will become apparent when referring, for a better understanding of my invention, to the following description taken in conjunction with the accompanying drawings, wherein:

Figure 1 is a plan view, with a part broken away, of an attachment device embodying features of my invention;

Fig. 2 is an enlarged broken sectional view of the structure illustrated in Fig. 1, taken on the line 2—2 thereof;

Fig. 3 is an enlarged broken sectional view of the structure illustrated in Fig. 1, taken on the line 3—3 thereof;

Fig. 4 is an enlarged end view of the structure illustrated in Fig. 1, as viewed from the left hand side thereof;

Fig. 5 is an enlarged sectional view of the structure illustrated in Fig. 1, taken on the line 5—5 thereof, with a part broken away;

Fig. 6 is an enlarged sectional view of the structure illustrated in Fig. 4, taken on the line 6—6 thereof; and,

Fig. 7 is an enlarged sectional view of the structure illustrated in Fig. 4, taken on the line 7—7 thereof.

In the figures, I have illustrated an attachment which comprises a base 10 which is bolted to the carriage of a grinding machine which may be fed laterally of the face of a grinding stone. It is to be understood that the base 10 may be the carriage of a grinding machine 15 when the device is built directly into a grinding machine. The grinding machine being a standard well-known form of equipment, is not herein illustrated or described.

The base 10 has a pair of bearings 11 and 12 mounted in projecting ends 13 for supporting a rocking bar 14 in the space therebetween. A tail stock 15 is mounted on the right hand end of the rocking bar 14, being adjustable along the bar to have the space between centers conform to the length of the workpiece.

A center 18 is carried by the tail stock operated longitudinally by a lever 17. The opposite end of the bar has a housing 18 secured thereto. The housing contains a support for a spindle 19 and drive mechanism for rotating the workpiece and for oscillating the housing and the rock bar 14. The workpiece is mounted on the spindles 18 and 19 and is rotated while being oscillated, or, through the elimination of the oscillating movement, the workpiece may be ground to cylindrical form.

A shaft 21 is mounted on bearings 22 supported within the housing, the one end having secured thereto a worm wheel 23. A worm 24 drives the worm wheel from a shaft 25 having an outboard bearing 26. A pinion 27 is slidably mounted on the shaft 21 and maintained in driving relation therewith by keys 28. The keys slide in keyways 29 extending a substantial distance along the shaft. The pinion is disposed between a bifurcated block 31 which is movable along the shaft by a bifurcated element 32 which spans the block and which extends through a slot 33 in the wall of the casing. A shaft 34 extends through the base web of the element 32 having an operating handle 35 mounted on its outer end. The bifurcated block 31 has an idler gear 36 in mesh with the pinion 27 and mounted on a stub shaft 37.

The bifurcated block 31 carries a gear sector 38 which is in mesh with a bevel gear 39 carried on the end of the shaft 34. By rotating the handle 35, the idler gear 36 is moved toward and away from one of a set of driven gears mounted on a shaft 41. The shaft 41 is mounted on bearings 42 within the housing in alignment with the shaft 21 and gears 43, 44, 45, 46, 47, 48, and 49 of the set, and secured thereto. The gears have teeth of the same pitch and pressure angle, the number of which increases from the gear 43 to the gear 49, respectively. The teeth of the idler gear 36 mesh with the teeth of the gears 43 to 49 inclusive, and through manipulation of the handle 35, may be moved into engagement with any one of the gears. In this manner, the driving of the shaft 41 may be changed relative to the speed of the driving shaft 21.

The left hand side of the shaft 41, as illustrated in Fig. 7, is provided with a gear 51 which is in mesh with a gear 52. The gear is secured to a sleeve 53 which may be employed to support a face plate, chuck, collet, or the like. The sleeve is rotatable on a spindle supporting hub 54 in which the center 19 is mounted. A rod 55 is mounted in the housing having an end 56 adjacent to the rear end of the center 19 by which the center may be loosened in the supporting hub 54. Ball bearings 57 are employed between the sleeve 53 and the hub 54 in a conventional manner.

A gear 58 is also mounted on the sleeve 53 having a lesser number of teeth than the gear 52 and which may be employed as the driving gear for the workpiece under certain conditions by removing the gear 51 and mounting another gear in mesh with the gear 58. The driving of the sleeve 53 through the gear 58, doubles the speed of rotation of the sleeve for a purpose which will be explained more fully hereinafter.

Referring again to the shaft 21, an oscillating mechanism 61 is mounted on the right hand end, as illustrated in Fig. 6. A plate 62 is keyed to the shaft 21 and is provided with a slot 63 presenting outwardly of the plate. A cam part 64 having on the outer periphery a recess 65 for roller bearings 66 is provided with a key-like projection 67

which extends within the slot 63 of the plate 62. An offset elongated opening 68 is provided in the body of the cam part 64 in which a cam 69 projects, mounted in off-center relation on the shaft 21 and secured in position by a washer 71 and nut 72. A dial 73 is provided on the exposed face of the cam part 64 over which an indicating pointer 74, mounted on the cam 69 moves when the cam 69 is adjusted to disclose the amount of eccentricity provided to the cam part 64. The rollers 66 engage the inner surface of an aperture 75 on one end of a link 76. The opposite end of the link is secured on a pin 77 which is mounted on a link 78 having one end secured to the base 18 by a pivot 79. A latch 81 projects over the end of the link 78 opposite to that mounted on the pin 77 and biased into engagement therewith by a spring 82. Adjacent to the latch 81 is a latch 83 which may engage a pin 84 on the side of the housing 18 when the latch 81 releases the link 78 and the housing is tilted upwardly to align the pin 84 with the latch 83.

With the parts in the position illustrated in the drawings, the operation of the device will now be described. It will be noted that the shaft 21 is connected to the shaft 41 through the pinion 27, idler gear 36, and the gear 45 of the set. The latch 81 engages the end of the link 78 and anchors the link 78 in fixed relation to the base 18. The cam 69 has been adjusted on the end of the shaft 21 to produce the proper degree of oscillating movement to the housing 18 which occurs about the center of the bearings 11 and 12 as the rocking bar 14 is oscillated therewith.

The elongated slot 63 in the cam part 64 permits the rotation of the cam 69 about the center of the shaft 21 to adjust the eccentricity of the cam part 64 which is prevented from rotating out of the particular position relative to the shaft 21 through the projection of the key-like projection 67 thereof in the slot 63 of the plate 62 which is keyed to the shaft. In the position illustrated, the center of the shaft is substantially on the center of the cam part 64. This is indicated by the pointer 74 being substantially on the 100 mark of the dial. By adjusting the cam 69 the center of the cam part 64 is shifted relative to the center of the shaft 21. By this adjustment the amount of eccentricity between the center of the cam part 64 and that of the shaft 21 is regulated which controls the degree of oscillation to the housing, rocking bar and therefore the workpiece.

When the center of the cam part 64 is exactly aligned with the center of the shaft 21, no tilting movement will occur to the rock bar 14 and the workpiece. To eliminate the necessity of making this adjustment when the workpiece is to be rotated only, the latch 81 is moved counterclockwise to release the link 78 and the housing, the rocking bar and the workpiece are tilted forwardly to a position in which the latch 83 engages the pin 84. In this position the eccentric movement is imparted to the link 78 only and the housing and the rocking bar are locked in the fixed position.

When driving through the gear 45 the rocking bar and workpiece are oscillated six times to one revolution of the workpiece. When a relief is to be ground on a tool having six cutting edges, the setting of the tool and the degree of oscillation is such relative to the grinding wheel as to produce machining from the cutting edge radially inward on a convex arc to relieve the cutting edge rearwardly a predetermined amount. The entire carriage and workpiece may be moved

laterally so that the entire length of the cutting blades are machined as the grinding operation proceeds. When a round bar is mounted between the centers 16 and 19 and the proper degree of oscillation produced in the rocking bar 14, a hexagon figure will be ground on the bar with all sides flat, of the same length and angular relation to each other. By a different adjustment of the cam, the sides could be made convex or concave to a degree conforming to the diameter of the grinding wheel 35.

By turning the handle 35 and shifting the element 37, any number of oscillations to one rotation of the workpiece may be obtained. With the structure herein illustrated, the gear 34 will produce two oscillations to one rotation of the workpiece while gears 44, 45, 46, 47, 48, and 49 will produce three, four, five, six, seven, and eight oscillations per single rotation, respectively. When the shaft 41 is driven through the gear 43, two flat sides may be ground on a workpiece or an oval of any flatness may be ground thereon, or two sides may be ground thereon which are convex. The different forms are obtained through the degree of oscillation provided to the rocking bar 14. The gear 44 produces a triangular figure on the workpiece, the sides of which may be flat, convex, or concave. The gear 45 will produce a four-sided figure. The gear 46 will produce a five-sided figure, the gear 47 will produce a six-sided figure, the gear 48 a seven-sided figure, and the gear 49 an eight-sided figure. It is to be understood that the sides of these figures may be made perfectly flat or they may be concave or convex, depending on the degree of oscillation applied to the rocking bar 14.

When a single flat, oval or cam shape is to be ground on a bar, the gear 51 is removed and a gear secured to the end of the shaft 41 which meshes with the gear 58. As pointed out hereinabove, the driving through the gear 58 increases the driving of the workpiece to twice the speed through the gear so that through driving of the shaft 41 by the gear 43 a single oscillation occurs

to the rocking bar 14 for each rotation of the workpiece. In this manner, geometric surfaces of accurate proportion with flat, convex or concave faces may be quickly ground on a workpiece while the latter is driven in rotation. By securing the rocking bar 14 against oscillation, a cylindrical surface may be ground on the workpiece.

While I have illustrated structure for grinding 10 geometric figures from one to eight sides on a workpiece, it is to be understood that by increasing the number of gears on the shaft 41 that figures of any number of sides may be ground by my device. This may embody the continuation 15 of the gear set herein illustrated, or where a series of figures having a large number of sides only are to be ground; the gear 49, or a larger gear, may be employed in place of the gear 43 and increasingly larger gears added to the shaft 41.

While I have described and illustrated but a 20 single embodiment of my invention, it will be apparent to those skilled in the art that various changes, omissions, additions and substitutions may be made therein without departing from the spirit and scope of my invention, as set forth in the accompanying claim.

What I claim is:

In a grinding device, a housing mounted for 25 pivotal movement, a work supporting shaft in said housing, a second shaft in said housing geared to said work supporting shaft, a third shaft in said housing, a plurality of gears associated with said second and third shafts for selectively changing the speed therebetween, a plate 30 on said third shaft having a slot, a cam part having a projection disposed in said slot and containing an elongated aperture, an eccentric on 35 said third shaft disposed in said aperture for adjusting the eccentricity of the cam part, and a link encompassing said cam part for causing said 40 housing to oscillate when one of said shafts is driven.

FRANK J. HORTON.
